UNITED STATES PATENT OFFICE

114,018

DESIGN FOR A GARMENT SUPPORTER

Florence M. Griffith, Albany, N. Y.

Application February 15, 1939, Serial No. 83,009

Term of patent 7 years

To all whom it may concern:

Be it known that I, Florence M. Griffith, a citizen of the United States, residing at Albany, in the county of Albany and State of New York, have invented a new, original, and ornamental Design for a Garment Supporter, of which the following is a specification, reference being had to the accompanying drawing, forming part thereof, and in which

Fig. 1 is a front elevation of a garment supporter showing my new design.

Fig. 2 is a side view thereof.

I claim:

The ornamental design for a garment supporter, as shown.

FLORENCE M. GRIFFITH.
